US0D1077033S

(12) **United States Design Patent** (10) **Patent No.:** **US D1,077,033 S**
(45) **Date of Patent:** **** May 27, 2025**

(54) **SUPPORT PLATE FOR CAMERAS**

(71) Applicant: **Arnold & Richter Cine Technik GmbH & Co. Betriebs KG**, Munich (DE)

(72) Inventor: **Jean-Frederic Fachon**, Munich (DE)

(73) Assignee: **Arnold & Richter Cine Technik GmbH & Co. Betriebs KG**, Munich (DE)

(**) Term: **15 Years**

(21) Appl. No.: **29/860,629**

(22) Filed: **Nov. 21, 2022**

(30) **Foreign Application Priority Data**

May 27, 2022 (EM) 009045123

(51) **LOC (15) Cl.** **16-05**

(52) **U.S. Cl.**

USPC **D16/242**

(57) **CLAIM**

The ornamental design for a support plate for cameras as shown and described.

DESCRIPTION

FIG. 1 is a front, left, top perspective view of a support plate for cameras, showing my new design;

FIG. 2 is a rear, right, bottom perspective view thereof;

FIG. 3 is a top elevational view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a bottom elevational view thereof;

FIG. 9 is a rear, right, top perspective view thereof; and,

FIG. 10 is a front, left, bottom perspective view thereof.

The features of the support plate for cameras shown in broken lines form no part of the claimed design.

1 Claim, 10 Drawing Sheets
